HEATER CONSTRUCTION

John W. Miller, Lansing, Mich., assignor to Motor Wheel Corporation, Lansing, Mich., a corporation of Michigan

Application May 23, 1938, Serial No. 209,414

7 Claims. (Cl. 126—67)

This invention relates to heaters, and more particularly to circulating type heaters which consist of an outer casing and a heat chamber within the casing.

5 It is an object of the invention to provide a heater which may be more conveniently assembled than previous heaters by constructing it in two separate units, which then may be attached together. Another object is to provide a heater 10 which is exceptionally rigid and in which the weight of the heat chamber and the burner is carried entirely by the corners of the outer casing. A still further object is to provide a novel means for tightly securing the burner within the 15 heat chamber.

These and other objects ancillary thereto will become more apparent in the following specification when read in connection with the attached drawing which forms a part thereof.

20 In the drawing:

Figure 1 is a front elevational view of the heater with parts broken away to show the interior construction of the lower portion thereof;

Figure 2 is a cross-sectional view taken on the 25 line 2—2 of Figure 1 and looking in the direction of the arrows;

Figure 3 is a fragmentary sectional view of a portion of Figure 2 on a much enlarged scale; and

30 Figure 4 is a cross-sectional view taken on substantially the line 4—4 of Figure 3.

The invention disclosed herein specifically resides in the construction of the outer casing and the supporting means for the burner and for the 35 heat chamber. The drawing shows the invention embodied in a heater of the circulating type.

In general, the heater consists of two assemblies, an outer casing and an inner heat unit. At the corners of the outer casing are four corner posts 11, which are of generally angular cross-section, provided at their edges with lateral flanges 12. Intermediate the corner posts 11 are panels 13. Preferably each of these panels 13 is flanged about its entire periphery in order to 40 stiffen the same and to provide means for securing the panels to the corner posts 11. As will be seen best in Figure 3, the panels 13 have flanges 15 at their vertical edges and horizontal flanges 14 on their lower edges. The flanges 15 of the 45 panels are joined to the adjacent flanges 12 of the corner posts 11 by means of bolts 16.

In order to securely brace the corners of the outer casing and to provide supporting members for the inner heater unit it is provided with four 50 obliquely arranged gussets 18. These gussets are

of the shape shown in Figure 3, and consist of webs 19 and flanges 20 and 21 at the edges of the web. The webs 19 of the gussets 18 are riveted to the lower flanges 14 of the adjacent panels 13 respectively by means of rivets 22. The 5 web 19 is notched at 23 and 24, and the metal of the web which is struck out to form the notches is bent vertically as at 25 and 26 to form ears which are bolted to the adjacent flanges 12 and 15 of the corner posts and side panels. 10

The outer casing is completed by the addition of a top wall 27 and bottom panels 28. The panels 28 fill in the space between the lower ends of the main panels and the floor on which 15 the heater stands.

The heater unit comprises a heat chamber 29 in which is mounted a pot type burner 30. The burner is not a part of this invention, and may be of any conventional type. Preferably, however, it is provided with a peripheral bead 31 20 adjacent the upper edge thereof, which seats against a peripheral bead 32 in the heat chamber. Then when the bead 31 is forced against the bead 32 by means to be described presently, an airtight joint will be formed. 25

Secured to the wall of the heat chamber 29 at four circumferentially spaced points are the legs 33. Each of these legs includes a vertical flange 34 which is attached to the wall of the heat chamber 29 by means of bolts 35. Each leg 33 30 also includes a vertically and radially extending web 36 and a horizontal flange 37. Preferably each leg is pressed from a single piece of metal. The outer end of the flange 37 is reinforced with 35 a relatively heavy metal plate 38 which may be spot welded thereto. The outer ends of the flanges 37 and the plates 38 are perforated for the reception of bolts 39. The legs 33 are secured to the webs of the gussets 20 by means of the bolts 39 and nuts 40, and constitute the sole 40 support for the heater unit.

In order to securely hold the burner 30 within the heat chamber, a supporting bar 41 is provided. The ends 42 of the bar are of angle shape, 45 as shown best in Figures 1 and 4, and the portion intermediate the angular ends is bowed downwardly, as shown in Figure 1. The bar 41 engages the bottom of the burner 30 adjacent the periphery. The ends 42 of the bar 41 are secured to the bottom flanges 37 of two diagonally opposite legs 33 by means of bolts 43 and nuts 44. The bar 41 is resilient and the ends 42 are bent so that they must be distorted in order to seat flat against the flange 37. Thus, 50 a resilient support for the burner is provided. 55

To secure the burner in the heat chamber it is merely necessary to place the shoulder 31 of the burner against the shoulder 32 of the heat chamber, then place the bar 41 in the position shown in Figures 1 and 4 and secure the same to the flanges 37 of the legs 33 by means of bolts 43 and nuts 44. When the nuts are drawn up securely the ends 42 of the bar 41 are distorted, and consequently, the burner is always held snugly, 10 yet resiliently, in the heat chamber.

It will be apparent that the outer casing comprising corner posts 11, panels 13, top wall 27, bottom panels 28 and gussets 18 may be assembled on one assembly line, and the heater unit 15 consisting of shell 29, burner 30, legs 33, and bar 41 may be assembled on another line. The heater unit may be then inserted in the casing, preferably while both are inverted, and secured by the four bolts 39 and nuts 40. In fact, this is 20 the preferred method of assembly.

It will also be noted that the sole support for the heater unit within the casing consists of the four legs 33. There is no need for any bracing of the upper end of the heater as has been 25 considered necessary heretofore. Hence, the heat chamber 29 may expand at a materially different rate than the outer casing without causing distortion of the heat chamber or outer casing.

30 The scope of the invention is indicated in the appended claims.

I claim:

1. A heater comprising an outer shell and an inner shell located within the outer shell, the outer shell including four upright corner posts of angular cross-section having lateral flanges at the edges thereof, a plurality of panels intermediate the corner posts, said panels having lateral flanges cooperating with and secured to the flanges on the corner posts, and a plurality of braces rigidly secured to the corner posts and also to the panels at points spaced from their points of connection with the corner posts, and means connecting the inner shell to the braces.
- 45 2. A heater comprising an outer shell and an inner shell located within the outer shell, the outer shell including four upright corner posts, and means for connecting the corner posts in spaced relation to each other, the inner shell including a plurality of depending legs, a burner located within the inner shell, and means for supporting the burner within the shell comprising a bar rigidly secured to the lower edge of the depending legs, and means connecting the legs to

the corner posts for supporting the inner shell thereon.

3. A heater cabinet comprising four upright corner posts of angular cross-section having lateral flanges at their upright edges, panels intermediate the corner posts, said panels having lateral flanges secured to the adjacent corner post flanges, generally horizontally extending braces at each corner of the cabinet secured to the flanges of the respective corner posts, and means 10 for securing the ends of the braces to the adjacent panels.

4. A heater cabinet comprising four upright corner posts of angular cross-section having lateral flanges at their upright edges, panels 15 intermediate the corner posts, said panels having lateral flanges secured to the corner post flanges, and braces at each corner, each brace having vertical flanges secured to the flanges of the respective corner posts, and a horizontal 20 web having its ends secured to the adjacent panels.

5. A heater comprising an outer shell and an inner shell located within the outer shell, the outer shell including four upright corner posts, 25 and means including corner braces for connecting the corner posts in spaced relation to each other, the inner shell having a plurality of depending legs, and means for securing said depending legs to the braces, said legs and said securing means 30 constituting the sole support for the inner shell upon the outer shell.

6. A heater comprising an outer shell and an inner shell located within the outer shell, the outer shell including upright corner posts, a 35 plurality of panels intermediate the corner posts, and a plurality of braces rigidly secured to the corner posts and to the panels at points spaced from their points of connection with the corner posts, and means connecting the inner shell to 40 the braces.

7. A heater comprising an outer shell including upright corner posts and means for connecting the corner posts in spaced relation to each other, said means comprising a plurality of corner braces secured to said corner posts, an inner shell located within said outer shell, said inner shell having a plurality of lateral projections adjacent its lower end and means securing said projections to said braces, said projections and 50 securing means constituting the sole support for the inner shell upon the outer shell.

JOHN W. MILLER.
